UNITED STATES PATENT OFFICE.

EARL C. FOGLE, OF ELKTON, VIRGINIA, ASSIGNOR OF ONE-THIRD TO EDWARD C. MARTZ AND ONE-THIRD TO JOHN W. MORRISON, BOTH OF HARRISONBURG, VIRGINIA.

BOTTLE FILLING AND CAPPING MACHINE.

1,418,146.

Specification of Letters Patent. Patented May 30, 1922.

Application filed April 22, 1920. Serial No. 375,801.

To all whom it may concern:

Be it known that I, EARL C. FOGLE, a citizen of the United States, residing at Elkton, in the county of Rockingham and State 5 of Virginia, have invented certain new and useful Improvements in Bottle Filling and Capping Machines; and I do hereby declare the following to be a full, clear, and exact description of the invention, such as 10 will enable others skilled in the art to which it appertains to make and use the same.

This invention relates to certain new and useful improvements in bottle filling and capping machines and has for its primary 15 object that as bottles are continuously fed through the machine in pairs or sets, they will be filled and capped.

Another object of the invention resides in the provision of a machine of the above 20 stated character in which each bottle will be filled with a mixture of a syrup and water fed thereto from separate gages as the bottle travels through the machine.

The invention has for another object, the 25 provision of a machine of the above stated character in which the bottles may be carried through the same on an endless conveyor and presented first to a syrup gage and then to a water gage, where the filling 30 operation is completed and the bottle capped or sealed, after which it is ready to leave the machine.

A further object of the invention resides in the provision of a machine of the above 35 stated character in which the syrup and water gages and also the capping mechanism may be mounted upon a supporting frame so that as one set of bottles receives the water and then the caps another set of 40 bottles is receiving the syrup from the syrup gages and an intermediate set already provided with the syrup is in a position between the syrup gages and the water gages ready to be moved into engagement therewith as 45 the filled and capped set moves on.

The invention has for a further object, the provision of a machine of the above stated character in which the gages for syrup and the water will be of such construction that 50 they may receive and pass on to the bottles only the proper quantity of syrup and water so that the relative proportions of syrup and water in the different bottles will be the same and only sufficient to fill the bottles.

55 The invention has for a further object, the

provision of a machine of the above stated character in which the bottles will be capped immediately upon receiving the water which completes the operation of filling of the bottles, and while the bottles are securely held 60 in engagement with the water gages.

The invention has for a still further object, the provision of a machine of the above 65 stated character in which all of the bottles to be filled are supplied with the syrup at each operation of the machine, will be moved into engagement with the syrup gages at the same time another set is moved into engagement with the water gages by raising of the reciprocating table over which the 70 bottles pass as they move beneath the gages.

A further object of the invention resides in the provision of a machine of the above 75 stated character in which the endless conveyor for the bottles may be actuated by a rocker frame upon each operation of the latter in one direction through which a new set of bottles is brought into position beneath the water gages and capping mechanism.

The invention has for a still further object, the provision of a machine of the above 80 stated character in which will be included means for automatically opening the syrup and water gages as the bottles move to position within the same to receive the contents 85 of the gages.

The invention has for a still further object, the provision of a machine of the above 90 stated character in which the gages will be automatically opened to receive a new supply of syrup and water during the rearward movement of the rocker frame and as new sets of bottles are brought to position beneath the gages.

The invention has for a still further object, the provision of a machine of the above 95 stated character in which caps will be automatically fed to the bottles as the filling operation is completed, a single cap being presented for each bottle and brought to position across the head of the bottle next to be automatically clamped thereon after completion of upward movement of the bottle toward the water gage from which the filling of the bottle is completed.

100 A still further object of the invention resides in the provision of a machine of the above stated character in which movement of all of the operative parts may be properly timed and in which both the rocker frame 110

and the reciprocating table will receive their force from a single power shaft.

The invention has for another object, the provision of a machine of the above stated character in which all of the operative parts may be mounted in a compact supporting frame and the rocker frame supporting member adjusted vertically upon the main frame members to adapt the machine for 10 filling and capping bottles of different sizes.

A still further object of the invention resides in the provision of a machine of the above stated character in which the feeding mechanism for the caps may be operated 15 from the main power shaft and the rocker frame moved back and forth to either operate or control operation of practically all of the operative parts of the machine.

Other objects of the invention will be apparent as the description proceeds and it will be understood that this invention consists in the novel construction, combination and arrangement of cooperating parts, as hereinafter more specifically set forth, 25 claimed and shown in the accompanying drawings forming a part of this application and in which:—

Figure 1 is a side elevation of the machine.

30 Figure 2 is a vertical enlarged transverse section on the plane of line 2—2 of Figure 1 and as indicated by the arrows.

Figure 3 is a top plan view of the complete machine.

35 Figure 4 is an enlarged vertical longitudinal section through the main portion of the machine, showing in dotted lines the endless conveyor and the bottles passing over the bottle raising table with the latter in its lowermost or unoperated position.

40 Figure 5 is an enlarged vertical section through one of the syrup gages and associated parts.

Figure 6 is an enlarged plan view of the 45 water gage supporting table and the parts carried thereby, one of the bottle actuated slide valves being shown in section.

Figure 7 is an enlarged vertical section 50 through one of the water gages and the parts connected therewith.

Figure 8 is an enlarged detail section 55 through the lower end of one of the water gages taken at right angles to Figure 7 and showing in dotted lines a bottle engaged with the water gage and a cap resting on this bottle to be clamped into position upon the bottle head.

Figure 9 is an enlarged detail vertical 60 section similar to Figure 8, with all of the parts in section to disclose the manner in which the cap is fed to the bottle and over the head thereof.

Figure 10 is an enlarged detail transverse section on the plane of line 10—10 of Fig-

ure 9, looking in the direction indicated by 65 the arrows, this figure disclosing the construction and cooperation of the capkicking means.

Figure 11 is an enlarged detail vertical section through one of the cap feeding tubes, 70 disclosing the mechanism for preventing the feeding of more than one cap to a bottle at a time and separating the caps as they travel downwardly in the cap feeding tube.

Figure 12 is a detail section, taken on the 75 plane of line 12—12 of Figure 6, looking in the direction indicated by the arrows, to disclose the construction of one of the bottle actuated valves employed in the syrup and water feed pipes leading to the gages.

Figure 13 is a detail section, of a portion 80 of one of the bottle operated valve arms, taken on the plane of line 13—13 of Figure 4.

Figure 14 is an enlarged fragmentary plan 85 of the endless bottle conveyor.

Figure 15 is an enlarged detail section taken on the plane of line 15—15 of Figure 1, looking in the direction indicated by the arrow, to disclose the manner in which the 90 endless bottle conveyor is operated from the rocker frame.

Figure 16 is an enlarged vertical section through one of the bottle cap hoppers taken on the plane of line 16—16 of Figure 2, 95 looking in the direction indicated by the arrow.

Figure 17 is a detail transverse section 100 through the cap hopper, taken on the plane of line 17—17 of Figure 16.

Figure 18 is a detail section through the agitating and feeding wheel, as shown on the plane of line 18—18 of Figure 16, looking in the direction indicated by the arrows.

Figure 19 is a detail plan view of one end 105 of the rocker frame, showing the relative positions of the various operating and actuating lugs carried thereby.

Figure 20 is an enlarged detail section on the plane of line 20—20 of Figure 2, showing the adjustable mounting of the rocker frame supporting members.

Figure 21 is a detail transverse section on the plane of line 21—21 of Figure 20.

Figure 22 is a detail section through the 115 cushioning and equalizing springs and spring cylinder provided for the pivot arm employed for operating the rocker frame actuating member.

Figure 23 is a top plan of the driving 120 shaft and the operating mechanism therefor, showing the mounting of the same in the lower part of the main supporting frame of the machine.

Figure 24 is a detail vertical section on the 125 plane of line 24—24 of Figure 23, looking in the direction indicated by the arrows.

Figure 25 is an enlarged detail section on

the plane of line 25—25 of Figure 23, looking in the direction indicated by the arrows.

Referring in detail to the drawings in which similar reference characters designate corresponding parts throughout the several views, 1 indicates the corner frame members of the supporting frame of the machine and 2 the lower longitudinal side frame members connecting the corner frame members in pairs. The corner frame members 1 may be connected by any other suitable longitudinal transverse connections and bracing bars, not shown. The longitudinal brace bars 2 have been shown in the drawings as the means to support upstanding shaft bearing plates 3 on opposite sides of the machine and lower transverse supporting bars 4, in order that the power shaft 5 of the machine and a differential driving gear mechanism 6 for the shaft 5 may be properly supported. These parts will be described in detail, later.

The main power shaft 5 of the machine has a fly wheel 7 mounted upon one end and 25 the belt wheel 8 upon its opposite end. The shaft 5 also has a cam member 9 mounted thereon intermediate its ends and is provided with an offset or crank portion 10 to one side of the cam member 9. A gear wheel 30 11 is mounted on the shaft 5 to the other side of the cam member 9. A pitman arm 12 is mounted on the offset or crank portion 10 of the shaft 5 while the gear wheel 11 meshes with and is driven by a gear wheel 35 13 carried by the shaft 14 of the differential gear mechanism 6. The shaft 14 also has a plurality of gear wheels 15 of different diameters mounted thereon and meshing with the driving gears 16 of different diameters 40 and which are loosely mounted upon the shaft 17 of the differential gear mechanism 6. The shafts 14 and 17 are mounted in bearings 18 carried by the lower transverse supporting bars 4, the shaft 17 having one 45 end extended through one of the plates 3 and provided with a main driving or belt wheel 19 which may be connected with any suitable source of power for operating the machine. Suitable stop collars 20 are secured to the shaft 17 to either side of the gear wheel 16 to prevent longitudinal movement of the latter upon the shaft 17, as 50 shown clearly in Figure 25 of the drawings. The shaft 17 is provided with the longitudinal key slot 21 and each gear 16 has a slot 22 extending therethrough and communicating with the central bore thereof so that the slot 22 of either gear wheel 16 may register with the slot 21 of the shaft 17 to receive 55 the enlarged portion 23 of the sliding key 24 movably positioned in the key slot 21 of the shaft 17. The key 24 has the end of its body or shank secured to the collar 25 which is slidably mounted upon the shaft 17 and

has the peripheral groove 26 in its outer face, 65 within which the sleeve 27 is engaged, said sleeve 27 being pivotally connected with the forked end 28 of the gear shifting lever 29, as shown at 30. This gear shifting lever 29 is pivotally mounted upon a stationary member 70 connected with the main frame, shown at 31 and has a locking member 32 for engagement with the locking segment 33 to lock the lever 29 in adjusted position by engagement of the locking member 32 of 75 the lever 29 with the segment 33 after the key 24 has been moved to bring the enlarged or working end 23 thereof into the slot 22 of the proper gear wheel 16 so that the machine may be driven or operated at the speed 80 desired.

The pitman arm 12 is formed in two sections the portion connected with the offset or crank section 10 of the shaft 5 having a piston head 34 formed on its opposite end 85 and engaged between the springs 35 and 36 within the cylinder 37, through which this section of the pitman arm or rod 12 is engaged, as clearly shown in Figure 22 of the drawings. The opposite or remaining section 90 of the pitman arm 12 has one end threaded as shown at 38 and threaded through the piston head 39, which latter is threaded upon the open end of the cylinder 37, thereby providing a resilient connection 95 between the sections of the pitman arm 12. The opposite end of the last mentioned section of the pitman arm 12 is pivotally connected with the rocker frame actuating rod 40, which is pivoted intermediate its 100 ends, as shown at 41, to the bracket member 42 carried by the transverse horizontal stationary plate 43, which latter is positioned between the corner frame members 1 and connected therewith, as shown at 44. This 105 transverse stationary plate 43 has the central opening 45 to accommodate the vertically reciprocating bottle raising table 46, as clearly shown in Figures 2 and 4 of the drawings.

The reciprocating bottle raising table 46 has a plunger 47 depending centrally from its lower face and engaged in the guide casing 48 secured to the under face of the stationary support 43 and extending transversely beneath the reciprocating bottle raising table 46, any suitable securing members 49 being provided for securing the guide casing 48 in position. The plunger 47 rests upon a spring 50 positioned in the guide casing 110 48 between the plunger 47 and the plunger head 51 of the table raising rod 52, said rod 52 having its upper end extended through a suitable opening 53 in the bottom of the guide casing 48 and the head 51 mounted on 115 this end of the rod 52, within the guide casing 48. The table raising rod 52 has a bifurcated lower end 53, within which is

pivotedly mounted or rotatably mounted a roller 54 which contacts with the peripheral or working edge of the cam member 9 on the power shaft 5, as clearly shown in Figure 5 2 of the drawings. It will therefore be seen that upon each rotation of the power shaft 5, the cam member 9 will force the table raising rod 52 upwardly, thereby compelling the rod 52 to raise the reciprocating bot- 10 the raising table 46 with the bottles riding over the same.

In order to assure proper guiding of the bottle longitudinally over the bottle raising reciprocating table 46, this table has mounted longitudinally upon its upper face the guide rail or track section 55 which has downwardly curved opposite end portions 56 and within the entire upper edge of the guide rail or track member 55 is provided 20 a groove 57 for the depending guide tongues 58 or guide fingers carried by the links 59 of the endless bottle conveyor. Stationary guide rails or track members 60 corresponding to the guide rail or track members 55 25 are mounted on the ends of the stationary transverse supporting member 43 and in alinement with the guide rail or track member 55. The guide rail or track members 60 are also curved downwardly at their ends 30 opposite the ends of the guide rail or track member 55, as shown at 61, thereby eliminating danger of the links 59 of the endless conveyor chain becoming caught on the end of the guide rail or track members during 35 operation of the same. Guide rail or track members 60 are provided with a guide groove 62 in their upper edge and in alinement with the guide groove 57 of the guide rail or track section 55 when the table 46 is in its lower- 40 most or unoperated position.

The link 59 of the endless conveyor chain has a bifurcated rear end 63 and a forwardly projecting tongue 64 formed on the forward end so that the links may be pivotally connected by suitable pivot pins 65 passed through the interlocking tongues 64 and bifurcated ends 63, as clearly shown in Figure 45 14 of the drawings. The links 59 also have side extensions 66 carrying bottle encircling 50 rings 67 so that each link may carry a pair of bottles across the reciprocating bottle table 46. It will be understood that the rings 67 are of sufficient size to encircle the largest sized bottle which the machine will accommodate and when smaller bottles are to be filled by this machine, rings or gasket members may be placed in the ring 67 to properly support a smaller bottle in upright position. The bottles to be filled by this machine have 60 been shown by dotted lines in several of the views and in full lines in Figure 2, in order that the operation of the machine may be more clearly understood. The bottles are designated by the letter A. Forward and

rear supporting tables 68 are mounted above the forward and rear end portions of the opening 45 in the transverse supporting member 43, by suitable supporting standards or posts 69 extending upwardly from the transverse supporting member 43 and preferably connecting with the corner portions of the gage supporting tables 68. The forward supporting table 68, as well as the rear gage supporting table 68 is composed of a lower section or half 70 and an upper section or half 71, the object of which will presently appear. Syrup gages 72, preferably four in number, are arranged in pairs above the forward supporting table 68 with their tapered discharge ends 73 projecting 80 through the tables 68. It will be understood that the table 68 is provided in each corner portion with a downwardly tapered gage receiving opening 74 to receive one of the syrup gages 72. Each gage is preferably of 85 cylindrical form and composed of brass or some other suitable material. Each syrup gage 72 has a removable screw cap 75 mounted in its upper end and through which is engaged a gage rod 76 having a head or 90 disk 77 mounted on its lower end and adapted to reciprocate in the lower portion of the gage 72. Upward movement of the rod 76 and disk or piston 77 is limited by stop nuts 79 adjustably threaded upon the rod 76 for 95 engagement with the under face or inner face of the cap 75. Each syrup gage is also provided with a transverse partition plate 80 in the upper part of its tapered discharge end 73 and a filling opening 81 in the side 100 of the syrup gage 72 above the partition plate 80 and a discharge opening 82 in the gage 72 below the partition 80. Each syrup gage 72 has a horizontal perforated ear 83 positioned upon one side to receive a turned 105 or hooked gage rotating member 84 to rotate the gage 72 within the table 68, as will be later fully described. Each syrup gage 72, when in one position, has its filling opening 81 registering with a syrup passage 85 110 formed in the opposed faces of the upper and lower halves 71 and 70 respectively of the table 68. The syrup feed passages 85 are preferably connected in pairs with their connected portions receiving a syrup tube 115 86 connecting with a syrup tank or the like, not shown. Each syrup feed passage 85 is normally closed by a transverse slide valve 87 working through the same and normally held in closed position with a solid portion 120 of the valve across the syrup feed passage 85, by means of a helical spring 88 positioned in the end of the valve chamber 89 in the table 68. When the valve 87 is moved to open position, however, the valve opening 125 90 registers with the syrup passage 85, permitting the syrup to be forced into the syrup gage 72, provided the filling opening 81

thereof registers with the syrup passage 85. A valve stem 91 is connected with each valve 87 and depends therefrom, the lower end of the valve stem 91 connecting with the 5 end of a valve operating arm 92, which is pivoted intermediate its ends upon a supporting bracket 93, which latter projects from one of the supporting standards or posts 69. The opposite or remaining end of 10 the valve operating arm 92 is curved, and preferably of arcuate form, as shown at 94, and extended in the path of movement of the bottles to be filled so that the valve may be operated by the bottles to be filled just previous to reaching a position beneath the 15 syrup gages 72, as will be clearly understood as the description proceeds. Each syrup gage 72, when in its other or emptying position, has both its filling opening 81 and its empty- 20 ing or discharge opening 82 registering with a curved connecting passage 95 in the table 68, a portion 96 of which is extended downwardly to provide for the passage 95. It will therefore be seen that when the fluid 25 or syrup gage 72 is in its emptying position, the contents thereof may be readily discharged from the open lower tapered discharge end 73.

The water gages 97 are mounted in the 30 rear gage supporting table 68 in a manner similar to the mounting of the syrup gages 72 in the forward table 68 and as the rear table 68 is of the same construction as the forward table 68, the parts thereof have 35 been correspondingly numbered and further detail description of the rear table 68 is thought to be unnecessary, at this time, as far as it corresponds with the forward table 68. The water gages 97 are of substantially 40 the same form as the syrup gages 72 and therefore corresponding parts are given the same reference characters in the drawings and further detail description of these parts, at the present time, is believed to be unnecessary. It may be stated however, that each 45 water gage 97 should be about twice the size of a syrup gage 72, as it is proposed to supply a bottle to be filled with twice as much water as syrup, although this may be varied 50 by proper adjustment of the disks 77 in the lower compartments of the syrup and water gages, as will be readily understood.

The lower ends of the water gages 97, where they extend through the openings 74 55 provided therefor in the rear table 68, are of inverted frusto-conical form and terminate in the end portions 98, having beveled or frusto-conical openings 99, at the upper end of which the lower partition plates 80 are 60 located, between the openings 81 and 82 of the water gages, as will be readily understood by referring to the drawings, particularly Figure 7. Around each water gage discharge end 98 is positioned a sleeve 100,

having a flanged upper edge 101 which is 65 secured to the under face of the rear table 68, by suitable securing members 102. The sleeve 100 extends a short distance below the end 98 of the water gage 97 and has a 70 collar 103 threaded upon its lower extremity and provided with an inturned lower end 104 which serves to support a rubber gasket 105 and hold the same in engagement with the lower end of the sleeve 100, the purpose 75 of which will presently appear. The sleeve 100 is further provided with a transverse bottle cap accommodating slot 106 above the collar 103 but below the discharge end of the water gage 97, whereby a cap may be 80 fitted to each bottle as the same is brought to position to receive the water from the water gage 97, as will be later fully described.

A slide valve 87, such as described for 85 controlling the feeding of the syrup to the syrup gages, is also employed in the water passage 85 of the rear table 68 to control the passage of water through the water gages 97, suitable water feed pipes 86 being 90 employed to conduct water from a suitable source of supply, not shown, to the connected water passages 85. The valve operating mechanism for the valve 87 in the water 95 passages 85 is the same as for the valve 87 of the forward table 68 and is therefore correspondingly numbered.

The bottle caps are fed into the sleeve 100 through cap feeding tubes 107 having curved lower ends 108 extended through the rear table 68, a transverse slot 109 being provided in the rear table 68 to one side of the water gage, as clearly shown in the drawings. The upper ends of the cap feeding tubes 107 for the pair of water gages 97 on each side of the machine are connected in 100 spaced relation, with the bottom of a cap hopper 109^a which has one vertical wall 110 and an opposite downwardly inclined wall 111, thereby providing a wide upper end and a narrow lower end or bottom for the hopper. 105 The two remaining sides of the hopper, designated by the numeral 112 are also downwardly inclined and suitable supporting or bracket arms 113 are secured to the last mentioned sides 112 of each hopper and 110 to the upper vertically adjustable longitudinal rails 114 of the main frame of the machine. It will be understood that two cap hoppers 109^a are provided and mounted in 115 parallel relation above the rear table 68. A shank 115 is mounted transversely through each hopper 109^a and has mounted thereon within each hopper a solid wheel or disk wheel 116 which is adapted for rotation in a circular opening 117 in the straight vertical side 110 of the hopper. A flat ring 118 is provided for each wheel, within the hoppers 109^a and spaced from the inner face

115

120

125

of the solid portion of the wheel 116, around the peripheral portion thereof by the cap separating ribs 119 extended radially across the face of the ring 118 opposite the solid or disk portion of the wheel in spaced relation. Each rib has opposite beveled side faces and a reduced extension 120 formed on its narrow face to connect the latter with the solid or disk portion 116 of the wheel. The ribs 119 are so spaced around the wheel that the distance between each pair of ribs 119 is equal to only a little more than the diameter of the bottle cap at the widest portion thereof. It will also be seen that by forming the ribs 119 in the manner described, each cap must turn against the solid or disk portion 116 of the wheel with its wide or open side thereagainst and its narrow or closed outer side toward the ring 118 before the bottle cap can pass downwardly between a pair of the ribs 119 and into one of the cap feeding tubes 107, it being understood that the transverse width of the hopper 109^a at the bottom thereof will not permit a cap to enter one of the cap feeding tubes 107 unless it is fed thereto by the wheel described, which serves to continually agitate the caps within the hopper 109^a, turn the caps and feed them into the feed tubes 107, as stated. The shaft 30 115 has a belt wheel 121 on an extended end, around which a drive belt 122 is engaged and which also extends around the belt wheel 8, previously described, whereby power may be transmitted from the main drive shaft 5 to the shaft 115 to cause continual rotation of the latter and the cap feeding wheels 116 within the hoppers 109^a, during operation of the machine. It will be apparent that by mounting the cap feeding wheels in the hoppers as described, they may be readily placed in position or removed as required.

The upper longitudinal frame members 114 are connected at their opposite ends by cross members 123, the extended ends 124 of which are slidably engaged between the guide and supporting rails 125 mounted on the inner faces of the corner members 1, adjacent the upper ends of the latter. Set screws 126 or the like are employed for securing the upper side members 114 of the frame, said set screws 126 being shown as threaded through one of the rails 125 of each pair and having clamping engagement with the extended ends 124 of the cross members 123. The extended ends 124 are also shown as being provided with upwardly and downwardly extended portions within the pairs of rails 125, as will be clearly understood by referring to Figures 20 and 21 of the drawings.

In order to prevent more than one cap being fed to the lower turned end 108 of any cap feeding tube 107, I have provided a cap separating mechanism for each tube

which includes a pair of fingers 127 which operate through the narrow side of the tube 107 and have transverse pins 128 in their outer ends which ride in elongated longitudinal slots 129 of a rock arm 130, which latter is pivoted centrally upon a pivot pin 131 mounted in a supporting bracket arm 132 projecting from the side of the tube 107. The arm 130 has rigidly connected to its central portion an inclined operating arm 133, adapted to be engaged by an operating lug 134. Arm 133 has a section 133^a, pivoted at 133^b, to permit lug 134 to pass the same in one direction so that arm 30 will not be operated by movement of lug 134 in one direction. The rock arm 130 is normally held in one position with the upper finger 127 projecting into the tube 107 to prevent the bottle cap within the tube 107 from passing to the lower end thereof, a spring 135 being shown as means for resiliently retaining the rock arm 130 in position, the spring 135 having one end connected with the upper portion of the rock arm 130 while its opposite end is connected with the tube 107. The mechanism just described is clearly shown in Figure 11 of the drawings and also Figure 9, and is to be duplicated for each tube 107.

In order that each cap should be brought to proper position over the top of the bottle for which it is intended, at the proper time, I have provided a cap kicking mechanism for use in connection with the tube 107 and which consists of a reciprocating cap engaging plunger 136, which has its main portion engaged through the transverse partition 137 in the horizontal chamber 138 formed on the lower end of the tube 107, the main portion of the cap engaging and kicking plunger 136 projecting into the lower turned end 108 of the tube 107, opposite the slot 106 of the sleeve 100. The free end or engaging end of the plunger 136 has a V-shaped recess 139 so that the plunger 136 may readily engage the side of the cap and kick the same into the sleeve 100 by way of the slot 106 till the cap projects partly over the top of the bottle entering the sleeve 100 as shown in the detail Figure 9, from which position the cap will be drawn by the bottle as the latter moves upwardly in the sleeve 100, until the cap is completely over the bottle at the end of the filling operation, when the cap will be clamped upon the bottle by the inclined walls 99 of the discharge end of the water gage 97 as the bottle continues in upward movement therein. The plunger 136 has an enlarged outer or rear end forming a head 140, rearwardly of the partition 137, to limit movement of the plunger 136 into the lower end 108 of the tube 107. A shank 141 projects outwardly from the head 140 and

has an enlarged outer end or disk head 142 formed thereon which is engaged by a corresponding disk or head 143 on the inner end of a reciprocating rod 144 which operates 5 through the rear end of the chamber 138. A spring 145 is engaged around the shank 141 and has one end bearing against the partition 137 while its opposite end bears against the disk or head 142 to resiliently retain the 10 plunger 136 in its outward or withdrawn position, permitting the cap released by the separating mechanism to travel downwardly in the tube 107 to a position opposite the slot 106 or with the cap partly projecting 15 through the slot 106, ready to be kicked into position over the top of the bottle. A reciprocating rod 144 has a bracket 146 formed on its outer end with a roller 147 mounted therein and this rod 144 is re- 20 silently retained in its outermost position by means of a spring 148 engaged there around and having one end bearing against the upper end of the chamber 138 while its opposite end bears against the bracket 25 146. The roller 147 is engaged at the proper time and forced inwardly to cause operation of the plunger 136, by a cam projection 149, which will be mentioned later.

As for operating the various movable 30 parts of this machine at the proper time, I have provided a rocker frame 150 which reciprocates or rocks back and forth over the tables 68 and is mounted upon the upper longitudinal rails 114 of the main frame, by 35 means of rollers 151 carried in the outturned ends of upstanding bracket arms 152, which latter are mounted on the longitudinal side bars 153 of said rocker frame 150, adjacent the ends of the latter, as clearly shown in 40 Figure 19 of the drawings. The rocker frame 150 has a forward depending frame 154 and a rear depending frame 154 surrounding the forward and rear tables 68, as will be readily seen by referring to the 45 drawings. Carried by the rocker frame 150, above the opposite longitudinal side of each depending frame 154, are the turned or hooked gage operating members 84, previously mentioned, thereby causing a turn of 50 each gage upon movement of the rocker frame 150 in either direction. It will be understood that the members 84 are arranged in spaced relation in pairs upon opposite sides of the rocker frame 150, as 55 shown in Figure 19 of the drawings. By referring to this figure, it will also be seen that this portion of the rocker frame 150, above the rear depending frame 154 has two of the separating mechanism operating lugs 60 134 arranged upon one side while the other pair of separating mechanism operating lugs 134 are carried by an arm 155 projecting from the end of the rocker frame 150, whereby the cap separating mechanism for

each tube 107 may be properly operated 65 upon movement of the rocker frame toward the forward end of the machine, to permit the lowermost cap to be released and travel to the slot 106 of the sleeve 100, as previously described. Attention is directed at 70 this time to Figures 9 and 11 of the drawings. Each depending frame 154 has a pair of the cam projections 149 mounted on the inner face of one longitudinal side member thereof, while the other pair of cam projections 149 are carried by an arm 156 projecting longitudinally from one end member of the depending frame 154. Each cam projection 149 is adapted to engage the wheel 147 contacting therewith and force the rod 144 upon which the wheel 147 is mounted inwardly to operate the cap plunger 136 in alinement therewith and thereby force the cap for the bottle through the slot 106 of the sleeve 100, upon each rearward movement of 75 the rocker frame 150 and at practically the end of such movement and thus after the bottles are filled.

The rocker frame 150 has an upwardly and rearwardly directed arm 157 secured to 90 its rear end and provided with a transverse pin 158 in its rear extended end, which rides in an elongated slot 159 in the upper end of the conveyor operating lever 160. This lever 160 is pivoted near its upper end, as shown at 161, to a supporting bracket 162 carried by a cross support 163 mounted on the upper longitudinal frame members 114, as shown in Figure 3 of the drawings. The lever 160 is also provided with a forked lower end 164 95 which is adapted to engage the endless conveyor on the rear side of the oppositely extended cross arms 66, previously described, and move the conveyor the proper distance each time the rocker frame 150 moves forwardly, to carry away the bottles which have received syrup from the syrup gages and those that have received water from the water gages and been capped, and move into 100 the place of these bottles, the next sets to be brought into engagement with the gages on the return or rearward movement of the rocker frame 150. Projecting from the forward end of the rocker frame 150 and centrally thereof, is the perforated ear 165, 115 through which is engaged the depending pin 166 carried by the oscillating arm 167, which latter has one end pivoted to the supporting bracket 168 mounted on one of the longitudinal upper frame members 114, while the 120 opposite end of the oscillating arm 167 extends across the other longitudinal upper frame member 114 and rests in the upper forked or bifurcated end 169 of the rocker frame actuating rod, whereby the rocker 125 frame 150 may be operated from the main operating shaft 5. In order to permit arm 160 at its lower end to move to the right of

extensions 66, as in Figure 1, it is made in sections pivotally connected together at 160^a to break joint on such movement to the right and to remain in rigid relation with each other during movement to the left.

As it is believed the complete operation of this machine will be clearly understood, without further detail description of the parts or explanation thereof, the operation 10 of the various parts will not be described in detail. The complete operation of the machine, however, may be briefly stated as follows.

The operative parts of the machine are so 15 arranged and timed that upon each forward movement of the rocker frame 150, caused by the rocker frame actuating rod 40, the water and syrup gages 97 and 72 respectively are given a quarter revolution to bring the 20 filling openings 81 thereof into registration with the passages 85 in the tables 68 to receive water and syrup respectively from their sources of supply. At the same time, the vertically reciprocating bottle raising 25 table 46 is permitted to drop by the wheel or roller 54 engaging and riding on the lower or small portion of the cam 9 and the lever 160 is actuated to move the conveyor chain so as to bring a bottle to position beneath 30 each of the water and syrup gages. As these bottles move to position beneath the gages, they contact with and operate the arcuate end 94 of the valve operating members 92, thereby opening the valves 87. It 35 may here be stated that the valve 87 can only be operated to permit the gages to be filled when a bottle is moving to position beneath the gages and therefore, should anything happen to one of the bottles before it 40 reaches the syrup gages or the water gages or should a bottle be left out or removed for any cause whatsoever the gages beneath which the bottle would have travelled can not be filled on this movement of the rocker 45 frame 150 and therefore could not waste the liquid on the next or return movement of the rocker frame 150. A forward movement of the rocker frame 150 also serves, as previously described to operate the bottle cap 50 separating mechanism for the cap feeding tube 107 leading to the sleeve 100 beneath the rear table 68 and surrounding the discharge ends of the water gages 97. As the cap agitating and turning wheels 116 in the 55 cap hoppers 109^a are operated continuously to drop the cap into the upper end of the feeding tube 107, there will always be a supply of caps above the cap separating mechanism of the tubes 107. Therefore, 60 upon the operation of the cap separating mechanism, of each tube, the lowermost cap in each tube 107 will be released and permitted to slide downwardly through the lower turned end 108 of the tube 107 and into 65 the slot 106 of the sleeve 100 for which it is

intended, ready to be kicked to proper position over the top of the bottle brought to position beneath the gage. It may be stated at this time that as the frame moves forwardly, a lug 134 thereon engages the depending arm 133 of the cap separating mechanism for each tube 107 and swing the rock arm 130 thereof so as to withdraw the upper finger 127 from beneath the lowermost cap feeding tube 107 and at the same time force inwardly the lower finger 127 to catch this cap. Immediately upon the completion of the forward movement of the rocker frame 150, however, the spring 135 of the cap separating mechanism will return the 70 rocker arm 130 with the upper and lower fingers 127 and the depending arm 133 to their normal position as the lug 134 moves away from the depending arm 133, thereby releasing the lowermost cap, upon the lower finger 127 and arresting downward movement of the remaining caps in the tube 107 and all of the caps above the same, permitting only the lowermost cap to slide down the curved or turned lower end 108 of the 80 tube 107.

The movement of the rocker frame 150 forwardly and the consequent operation of the parts of the machine just described will take place during a part of the complete revolution of the operating shaft 5 and while the wheel or roller 54 is riding upon the small portion of the cam 9. During the remainder of the revolution of the operating shaft 5, however, the roller 54 rides upon the large portion of the cam 9, thereby resulting in an upward movement of the vertical reciprocating bottle raising table 46 to raise the bottles which have been brought to position thereover and bring the four bottles on the forward end of the table 46 into engagement with the four syrup gages of the tube while the four bottles on the rear end of the table are brought into engagement with the water gages 97, the bottles which have just been moved rearwardly from position beneath the syrup gages 72 resting upon the central portion of the reciprocating bottle raising table 46, as clearly shown in Figures 1 and 4 of the drawings. During the operation of the revolution of the operating shaft 5, the rock frame 150 is moved rearwardly, and as the rock frame 150 moves rearwardly, the syrup gages 72 and water gages 97 are given a quarter turn 110 in the reverse direction, thereby closing communication between the filling openings 81 thereof and the liquid passages 85 of the tables 68 and opening communication between said filling openings 81 of the gages and the passages 95 in the tables 68, the discharge openings 81 of the gages being also at this time brought into communication with the passages 95, as clearly shown in Figure 9 of the drawings, thereby permitting the 115 120 125 130

gages to discharge their contents into the bottles there beneath as the bottles move upwardly towards said gages. After the bottles are filled, the cap kicking mechanism for 5 tubes 107 is operated through rearward movement of frame 150 to kick a cap through each slot 106 in the sleeves 100 and to proper position over the bottles being brought toward the said gages 97 and as these bottles 10 receive their supply of water from said water gages 97 to complete the filling operation of the bottles. As the bottles on the rear end of the vertically reciprocating bottle raising table 46 complete their upward movement 15 with the table, the caps engaged across the same are caught by the ends of the bottle neck or head and drawn to proper position across the same so that the caps are securely clamped over the heads of the 20 bottle necks as the latter move through the sleeves 100 into the discharge ends of the water gages 97, the caps being clamped by the beveled walls 99 of the discharge ends 98 of said water gages 97; as previously described 25 in detail. Attention may be called at this time to the fact that the syrup will be properly directed from the syrup gages 72 into the bottles there beneath owing to the form of the discharge ends of said syrup 30 gages 72 while the gaskets 105 will prevent waste of the water discharged from the water gages 97 to the bottle moving toward the same, as each bottle projects through the gasket 105, as clearly shown in 35 Figures 8 and 9 of the drawings. By the time the main drive shaft 5 has completed its revolution and the widest part or point of the cam 9 is contacting with the roller 54, all of the bottles on the ends of the bottle 40 reciprocating raising table 46 will have received their fluid from the gages 72 and 97 and those that have been filled by the water gages 97 will have also had their caps clamped thereon so that as soon as the point 45 of the cam 9 passes from beneath the roller 54, the table 46 will return to its lowermost position with the filled and partially filled bottles resting on the end thereof and withdrawn from engagement with the syrup 50 gages 72 and the water gages 97. Then, as the main operating shaft 5 is making the first half of its second revolution, the rock 55 frame 150 is again moved forwardly, causing operation of the parts as described for the first half of the first revolution of the main shaft 5. The rocker frame 150 is then moved rearwardly upon the second half of the second revolution of the main operating shaft 5, and the next set of bottles supplied 60 with syrup and water and capped as described for the second half of the first revolution of the main operating shaft 5. This operation is repeated as described for each revolution of the main operating shaft 65 5, as long as the machine is operated and it

is therefore believed that further description of the construction and operation of the parts of this machine will be unnecessary.

While the preferred embodiment of the invention has been shown and described, it will 70 be understood that minor changes in the details of construction and arrangement of parts may be resorted to within the scope of the appended claims without departing from the spirit of the invention.

What is claimed is:—

1. A bottle filling and capping machine comprising a supporting frame, stationary tables mounted in said supporting frame, a vertically movable table beneath said stationary tables, a rocker frame movable longitudinally above said stationary tables, fluid gages arranged in pairs in said stationary tables, gages of one stationary table serving to only partially fill bottles brought into engagement therewith, the gages carried by the remaining stationary table serving to complete the filling operation, means for conveying bottles across said vertically movable table, a main operating shaft, means controlled by said main operating shaft to raise said vertically movable table to bring certain of the bottles upon said vertically movable table into engagement with the two sets of fluid gages, means controlled by said main operating shaft to operate said rocker frame, and means to supply a cap for each bottle at the completion of the filling operation thereof.

2. A bottle filling and capping machine 100 comprising a supporting frame, a stationary frame member extended transversely in said supporting frame, a movable table normally resting in said stationary frame member, spaced forward and rear stationary tables 105 above said movable table, an endless conveyor for carrying bottles across said vertically movable table, syrup gages mounted in said forward stationary table, water gages mounted in said rear stationary table, a 110 rocker frame reciprocally mounted above said stationary tables, means controlled by said rocker frame to operate the bottle conveying means upon movement of said rocker frame in one direction, means for raising 115 said vertically movable table to bring certain of said bottles into engagement with said syrup gages and said water gages, means controlled by said rocker frame to move said gages to their receiving and discharging positions, and means for supplying a cap for each bottle brought to engagement with said water gages.

3. A bottle filling and capping machine 125 comprising a supporting frame, a stationary frame member, extended transversely in said supporting frame, a movable table normally resting in said stationary frame member, spaced forward and rear stationary tables above said movable table, an endless con- 130

veyor for carrying bottles across said vertically movable table, syrup gages mounted in said forward stationary table, water gages mounted in said rear stationary table, 5 a rocker frame reciprocally mounted above said stationary tables, means controlled by said rocker frame to operate the bottle conveying means upon movement of said rocker frame in one direction, means for raising 10 said vertically movable table to bring certain of said bottles into engagement with said syrup gages and said water gages, means controlled by said rocker frame to move said gages to their receiving and discharging 15 positions, means for supplying a cap for each bottle brought into engagement with said water gages, and means controlled by each bottle to open the gages and permit filling thereof as the bottles move to position 20 beneath said gages.

4. A bottle filling and capping machine comprising a supporting frame, a transverse frame member within said supporting frame and provided with a central opening, a vertically movable table normally resting in 25 said opening, forward and rear stationary tables above said vertically movable table, syrup gages mounted in said forward stationary table, water gages mounted in 30 said rear stationary table, a main operating shaft, a rocker frame above said stationary tables, means for conveying bottles across said vertically movable table, means operated by said rocker frame to actuate the last 35 mentioned means, means controlled by said main operating shaft to cause a forward movement and a return movement of said rocker frame upon each revolution of said main operating shaft, means controlled by 40 said main operating shaft to raise said table once during its revolution of said main operating shaft to bring the forward bottle on said vertically movable table into engagement with said syrup gages to be partially 45 filled thereby and at the same time bring the rear bottles on said vertically movable table into engagement with said water gages to complete the filling of said bottles with 50 water, and supporting means for said rocker frame mounted in said main supporting frame.

5. A bottle filling and capping machine comprising a supporting frame, a transverse frame member within said supporting frame and provided with a central opening, a vertically movable table normally resting in 55 said opening, forward and rear stationary tables above said vertically movable table, syrup gages mounted in said forward stationary table, water gages mounted in said rear stationary table a main operating shaft, a rocker frame above said stationary tables, means for conveying bottles across said vertically movable table, means operated by said 60 rocker frame to actuate the last mentioned 65

means, means controlled by said main operating shaft to cause a forward movement and a return movement of said rocker frame upon each revolution of said main operating shaft, means controlled by said main operating shaft to raise said table once during each revolution of said main operating shaft to bring the forward bottle on said vertically movable table into engagement with said syrup gages to be partially filled thereby 75 and at the same time bring the rear bottles on said vertically movable table into engagement with said water gages to complete the filling of said bottles with water, supporting means for said rocker frame 80 mounted in said main supporting frame, and means for supplying the filled bottle with a cap as the filling operation is completed.

6. A bottle filling and capping machine comprising a supporting frame, a transverse frame member within said supporting frame, said transverse frame member having a central opening, a vertically movable table within said opening, means for moving bottles across said transverse frame member 85 and said vertically movable table in pairs and sets, a main operating shaft for controlling the last mentioned means, means controlled by said main shaft for raising said table, a rock frame above said vertically 90 movable table, operative connections between said main operating shaft and said rock frame, means for operating the bottle moving means being connected with said rock frame, gages supported above said vertically 95 movable table, means actuated by said rock frame and the bottles to cause a filling of the gages and discharging of the contents thereof into the bottles as the latter are raised by the table in engagement with said 100 gages, means for guiding the bottle moving means, and means for guiding and resiliently supporting said vertically movable table and preventing a sudden return of the vertically 105 movable table to its lowermost position.

7. A bottle filling and capping machine comprising a supporting frame, a transverse frame member within said supporting frame, said transverse frame member having a central opening, a vertically movable table within said opening, means for moving bottles across said transverse frame member and said vertically movable table in pairs and sets, a main operating shaft 115 for controlling the last mentioned means, means controlled by said main shaft for raising said table, a rock frame above said vertically movable table, operative connections between said main operating shaft and said rock frame, means for operating 120 the bottle moving means being connected with said rock frame, gages supported above said vertically movable table, means actuated by said rock frame and the bottles to cause a filling of the gages and discharge of the 125 130

- contents thereof into the bottles as the latter are raised by the table in engagement with said gages, means for guiding the bottle moving means, means for guiding and resiliently supporting said vertically movable table and preventing a sudden return of the vertically movable table to its lowermost position, and means for supplying a cap for each bottle filled.
- 10 8. A bottle filling and capping machine comprising a supporting frame, a transverse frame member within said supporting frame, said transverse frame member having a central opening, a vertically movable table within said opening, means for moving bottles across said transverse frame member and said vertically movable table in pairs and sets, a main operating shaft for controlling the last mentioned means, means controlled by said main shaft for raising said table, a rock frame above said vertically movable table, operative connections between said main operating shaft and said rock frame, means for operating the bottle moving means being connected with said rock frame, gages supported above said vertically movable table, means actuated by said rock frame and the bottles to cause a filling of the gages and discharging of the contents thereof into the bottles as the latter are raised by the table into engagement with said gages, means for guiding the bottle moving means, a cap feeding mechanism for feeding caps to the bottles as the latter are filled to be clamped on the head of the bottle neck as the bottle is forced into engagement with the last gage from which it is to receive a liquid.
9. A bottle filling and capping machine comprising a supporting frame, a transverse frame member within said supporting frame, said transverse frame member having a central opening, a vertically movable table within said opening, means for moving bottles across said transverse frame member and said vertically movable table in pairs and sets, a main operating shaft for controlling the last mentioned means, means controlled by said main shaft for raising said table, a rock frame above said vertically movable table, operative connections between said main operating shaft and said rock frame, means for operating the bottle moving means being connected with said rock frame, gages supported above said vertically movable table, means actuated by said rock frame and the bottles to cause a filling of the gages and discharging of the contents thereof into the bottles as the latter are raised by the table into engagement with said gages, means for guiding the bottle moving means, a cap feeding mechanism for feeding a cap to each bottle between the bottle and the last gage with which the bottle is brought into engagement, said last gage having its neck formed so as to clamp the caps on to the bottle as the latter is forced into engagement with the gage.
10. A bottle filling machine comprising a supporting frame, a main operating shaft for said supporting frame, fluid gages mounted above said main operating shaft, a rock frame surrounding said fluid gages and adapted for movement longitudinally of said frame, means for moving bottles to position beneath said fluid gages, means for moving said bottles into engagement with said gages, means for feeding caps to the bottles as they are brought to engagement with certain of said gages, means carried by said rock frame for controlling the feeding of the caps to said bottles, and means for operating said rock frame from said main operating shaft.
11. A bottle filling machine comprising a supporting frame, a transverse member in said supporting frame, a supporting table mounted above said transverse supporting member, said table being composed of upper and lower sections, water gages rotatably mounted within said tables, registering water passages formed in the opposed faces of said supporting table section, a rock frame above said supporting tables, means for operating said rock frame to move said gages to their filling and discharging position, means for bringing bottles into engagement with said gages, and means for supplying caps to said bottles during the filling operation thereof to be clamped upon the bottles as the latter are forced into engagement with said gages.
12. A bottle filling and capping machine comprising sectional gage carrying tables, each table being formed of upper and lower sections, water and syrup gages mounted in said gage carrying tables, water and syrup passages formed in said tables and leading to said gages, valves normally closing said passages, means for rotating said gages within said tables to bring the latter to their filling positions and their discharging positions, means for moving bottles to position opposite said gages, means controlled by movement of said bottles to open the valves in said passages, means for raising the bottles into engagement with said gages, and means for supplying caps to said bottles as they are brought into engagement with certain of said gages.
13. A bottle filling and capping machine comprising a supporting frame, a transverse supporting member for said frame, upper supporting members in said frame, a rock frame mounted on the upper frame members for movement longitudinally of the supporting frame, an operating shaft, connections between said operating shaft and said rock frame to actuate the latter in each direction upon each revolution of the operating shaft, water and syrup gages mounted above the transverse supporting member, means

for moving bottles over said transverse supporting member, means for raising bottles as they pass through the machine over the transverse supporting member, driving connections for the last mentioned means controlled by operation of the operating shaft, actuating means for the bottle moving means controlled by the rock frame, and cap feeding mechanism mounted above the rock frame to feed caps to certain of the bottles brought into engagement with the gages.

14. A bottle filling and capping machine comprising a supporting frame, water and syrup gages mounted in said frame, means for supplying water and syrup to said gages, means for controlling the supply of water and syrup to said gages, means for moving bottles in sets through the machine beneath the syrup gages, the fluid supply controlling means being adapted to be operated by said bottles moving to position opposite the gages, means for moving said gages to their filling positions and returning said gages to their emptying positions, means for controlling operation of the last mentioned means, a main operating shaft controlling the last mentioned means, means controlled by the main operating shaft to raise the bottles in sets into engagement with said gages as the contents of the latter is discharged into said bottles, means for supplying caps to the bottles as the latter are filled, and means for varying the speed of rotation of the main operating shaft.

15. A bottle filling and capping machine comprising a main supporting frame, a transverse member within said main supporting frame, a movable table within said transverse supporting member, a transverse drive shaft mounted in said supporting frame, a cam raising mechanism for said table, said cam raising mechanism being carried by said drive shaft and adapted to raise the table upon each complete revolution of said drive shaft, a rock frame mounted in said supporting frame, an oscillating member connected with said rock frame to actuate the latter, connections between said oscillating member and said drive shaft to cause the complete operation of the rock frame and a return of the same to normal position upon each complete revolution of the drive shaft, means actuated by the rock frame to move bottles across said table, gages mounted above said table to supply a syrup and water to said bottles in turn, said table being adapted to move the bottles upwardly in sets into engagement with said syrup and water gages, means controlled by the movement of the rock frame to move the syrup gages to their filling and emptying positions, and cap feeding mechanism operated by said operating shaft to feed caps to the bottles as they receive water from the water gages.

16. A bottle filling and capping machine

comprising a main supporting frame, a transverse member within said main supporting frame, a movable table within said transverse supporting member, a transverse drive shaft mounted in said supporting frame, a cam raising mechanism for said table, said cam raising mechanism being carried by said drive shaft and adapted to raise the table upon each complete revolution of said drive shaft, a rock frame mounted in said supporting frame, an oscillating member connected with said rock frame to actuate the latter, connections between said oscillating member and said drive shaft to cause the complete operation of the rock frame and a return of the same to normal position upon each complete revolution of the drive shaft, means actuated by the rock frame to move bottles across said table, gages mounted above said table to supply a syrup and water to said gages in turn, said table being adapted to move the bottles upwardly in sets into engagement with said syrup and water bottles, means controlled by the movement of the rock frame to move the syrup gages to their filling and emptying positions, cap feeding mechanism operated by said operating shaft to feed caps to the bottles as they receive water from the water gages, and means for separating the caps in the cap feeding means and releasing one cap at a time for each bottle filled by the machine.

17. A bottle filling machine having a dispensing mechanism, a table, a conveyor to move bottles along the table to cooperate with the dispensing mechanism, a frame, means to rock the frame, a bottle cap dispensing mechanism operable by the frame, and means operable by movement of the frame to advance the conveyor.

18. A bottle filling machine having a dispensing mechanism, a conveyor to move bottles, a table to support the bottles, a frame, means to rock the frame consisting of a lever, means to actuate the lever, and a lever operable by said frame to advance the conveyor.

19. A bottle filling machine having a dispensing mechanism, a table, a conveyor for bottles on said table, a track on said table for the conveyor, a table operable to move the bottles toward the dispensing mechanism also having a track, inter-engaging means between the conveyor and tracks, and the conveyor being flexible to permit movement of the second mentioned table.

20. A bottle filling machine having a dispensing mechanism, a table to support bottles, a conveyor for the bottles, a track on the table for the conveyor, a table operable to move the bottles toward the dispensing mechanism, a track on the movable table, said track being provided with grooves, and depending means on the conveyor entering

said grooves, and said conveyor being flexible to permit movement of the second mentioned table.

21. A bottle filling machine having a dispensing mechanism, a table to support the bottles, a conveyor for the bottles, a track on the table for the conveyor, a table operable to move bottles toward the dispensing mechanism having a track, each of said 10 tracks having a groove, said conveyor con-

sisting of links, means pivotally connecting said links, and tongues depending from said links into said grooves.

In testimony whereof I affix my signature in presence of two witnesses.

EARL C. FOGLE.
